(57) **CLAIM**

The ornamental design for a truck hood damper, as shown and described.

DESCRIPTION

FIG. 1 is a front view of a truck hood damper showing my new design;

FIG. 2 is a rear view of the truck hood damper;

FIG. 3 is a right side view of the truck hood damper;

FIG. 4 is a left side view of the truck hood damper;

FIG. 5 is a top view of the truck hood damper;

FIG. 6 is a bottom view of the truck hood damper; and,

FIG. 7 is a top front side perspective view of the truck hood damper.

The broken lines illustrate a boundary of the claimed design, as well as portions of the truck hood damper which form no part of the claimed design.
